(57) **CLAIM**

The ornamental design for a vehicle wheel, as shown and described.

DESCRIPTION

FIG. 1 is a perspective view of a vehicle wheel illustrating our new design.

FIG. 2 is a front elevation view of a vehicle wheel illustrating our new design; and,

FIG. 3 is a side elevation view of a vehicle wheel illustrating our new design.

The broken lines in the drawings depict portions of the vehicle wheel that form no part of the claimed design.

1 Claim, 3 Drawing Sheets

FIG. 1

FIG. 2

FIG. 3
